UNITED STATES PATENT OFFICE.

WALTON SMITH, OF RIDLEY PARK, PENNSYLVANIA, ASSIGNOR TO JAMES S. THOMPSON, OF NORTH TONAWANDA, NEW YORK.

TELEPHONE-EXCHANGE SYSTEM.

SPECIFICATION forming part of Letters Patent No. 650,548, dated May 29, 1900.

Application filed June 9, 1899. Serial No. 719,879. (No model.)

To all whom it may concern:

Be it known that I, WALTON SMITH, a citizen of the United States, residing at Ridley Park, in the county of Delaware and State of Pennsylvania, have invented new and useful Improvements in Telephone-Exchange Systems, of which the following is a specification.

This invention relates to a telephone-exchange system in which the electric generator or source of energy for operating the speaking apparatus of the different subscribers is all located at the central office instead of locating a generator for this purpose at each subscriber's station, this arrangement of the generators being commonly known as the "central-energy system."

One of the objects of this invention is to provide a generator system of this character in which the electric energy is applied uniformly to the speaking apparatus of two parties who are conversing and is only in use when two parties are connected with each other.

My invention has the further object to avoid the induction between the main lines of the subscribers and adjacent electric wires, thereby improving the transmission of speech and permitting conversation to be carried on without interference from cross-talking or other electrical disturbances.

In the accompanying drawings, consisting of two sheets, Figure 1 is a sectional view showing my improvements applied to a telephone-switch system in which the main line is opened when the subscriber calls up the central office. Fig. 2 is a fragmentary view showing the circuits of the operator's listening and talking apparatus. Fig. 3 is a fragmentary sectional view showing my improvements applied to a telephone-switch system in which the main line is not opened when a subscriber calls up the central office.

Like letters of reference refer to like parts in the several figures.

Referring to Fig. 1, A represents the inclosing case of a subscriber's apparatus; B, the signal-generator; C, the bell-coils; D, the telephone-receiver; E, the microphone or transmitter; F, the induction-coils, and H 50 the vertically-movable switch-lever, which is depressed when the telephone is hung upon

the same or is raised by a spring h when the telephone is removed therefrom. All of these parts may be of ordinary construction.

g is a ground-contact which is connected by 55 a wire g' with the ground G and which is engaged by the switch-lever when the latter is depressed. One end of the generator-coils is connected with a generator-contact b, which is engaged by the switch-lever when the latter 60 is depressed. The other end of the generator-coil is connected by a wire c with one side of the bell-coils. One side of the transmitter is connected by a wire d with the opposite side of the bell-coils, and the other side of the 65 transmitter is connected by a wire d' with one end of the primary induction-coil f. The opposite end of the primary coil is connected by a wire d² with a transmitter-contact d³, which is engaged by the switch-lever when 70 the latter is raised. The ends of the coil in the telephone or receiver are connected by wires f' f² with the secondary induction-coil f³.

I and K represent the main lines, whereby each subscriber's station is connected with 75 the central office and with another subscriber's station. The wire I is connected with the bell-coils on the side opposite to that with which the generator-coil is connected, and it is connected with the transmitter-wire d, so 80 that the current from the wire I can pass either through the bell-coils and generator, which constitute the essential parts of the signaling apparatus, or through the transmitter and primary induction-coil, which form 85 part of the talking apparatus. The wire K is connected only with the switch-lever. When the receiver is hung upon the switch-lever, the latter is disengaged from the transmitter-contact d³ and depressed into engagement with the ground and generator contacts g and b, and when the receiver is removed the switch-lever is raised by the spring h out of engagement with the contacts g and b and into engagement with the contact d³. 95

The annunciators of the subscribers are mounted on upright switchboards l at the central office, and each consists, essentially, of a plunger l', provided at its front end with a visual indicator head or button, a pivoted 100 catch l², adapted to engage with the plunger and hold the same in a retracted position, an

armature b^3 , connected with said catch, a pair of coils b^4 , which when energized attract said armature and disengage the catch from the plunger, and a spring b^5 , whereby the plunger 5 is projected when released.

M represents the coupling-jacks, one or more of which are arranged in each subscriber's line at the central office and which receives the plug of the operator's listening or 10 signaling apparatus or the coupling-plugs N of other subscribers. These jacks are arranged on the vertical switchboard and may be of any usual or well-known construction, each of the jacks shown in Fig. 1 consisting, 15 essentially, of a socket-contact m and a spring-contact m' , which is adapted to be engaged with and disengaged from the socket-contact.

The wire I of each subscriber runs directly to the socket-contact m of its coupling-jack. 20 The other member m' of its coupling-jack is connected by a wire o with one end of the subscriber's annunciator-coils, the opposite end of the annunciator-coils being connected with an insulated contact o' , which is adapted to be engaged by a contact o^2 on the plunger when the latter is in its retracted position. 25

The coupling-plug N of each subscriber is provided with two contacts n n' , which are adapted to engage, respectively, with the two 30 members m m' of the coupling-jack of another subscriber.

p p' represent the two members of a divided contact-seat, which are adapted to support the plug of the subscriber when not in use and 35 which are electrically connected by a bridge p^2 , formed, preferably, by the metallic base on the lower end of the coupling-plug. When the coupling-plug is not in use, the same is held with the bridge p^2 on its base against the 40 contacts p p' by a cord P, which is connected with its ends to the plug and the switchboard and a weight p^3 , provided with a roller, which engages with the bight of the cord. Two wires p^4 p^5 are arranged in the cord. The wire p^4 45 is connected at one end with the plug-contact n' and at its other end with the main wire K and by a branch wire p^6 with the bridge-contact p . The other cord-wire p^5 is connected at one end with the plug-contact n and at its 50 other end by a wire p^7 with the frame of the annunciator and by a branch wire p^8 with the bridge-contact p' . The plunger carrying the contact o^2 is in metallic contact with the annunciator-frame to which the wire p^7 is connected, so that the frame and plunger form a 55 part of the electric conductor.

Q represents an electric generator or battery which supplies the current for operating the talking and listening apparatus of two 60 connected subscribers. Each subscriber is preferably provided with an individual battery of sufficient power to supply the necessary current for operating the talking and listening apparatus of the two subscribers 65 having the longest lines in the system. The battery is arranged at the central office and is included in one of the wires of the plug-cord,

the same being shown included in the cord-wire p^4 in Fig. 1.

The operator's listening and talking apparatus, as shown in Fig. 2, consists, essentially, of a telephone or receiver R, a transmitter S, a pair of induction-coils T, an electric battery or generator U, and a coupling-plug V. The coupling-plug V is provided with a central 70 contact v' and a surrounding insulated contact-sleeve v , and these contacts are respectively connected by main circuit-wires v^2 v^3 with one end of the primary induction-coil t and one side of the transmitter. The other 75 end of the primary induction-coil is connected with the opposite side of the transmitter by a wire u, which includes the electric battery U. The opposite ends of the secondary induction-coil t' are connected by wires r r' 80 with opposite ends of the coil in the receiver or telephone and complete the operator's local circuit.

If a subscriber whose line is in normal condition operates his signaling apparatus for 85 calling up the central office, the circuit is as follows: Beginning at the contact b on one side of the generator, the current passes successively through the switch-lever H, main wire K, branch wire p^6 , contact p , bridge p^2 , 90 contact p' , branch wire p^8 , wire p^7 , annunciator-frame, plunger b' , contacts o^2 o' , annunciator-coils, wire o, coupling-jack contacts m m' , main wire I, bell-coils, wire c, and through the generator-coil to contact b . This 95 current energizes the annunciator-coils of the subscriber at the central office, thereby releasing the plunger and permitting the same to be projected by its spring, whereby the operator is informed that the subscriber has 100 called up, and at the same time the circuit is broken by the separation of the contacts o^2 o' , and the subscriber by reason of his bell 105 stopping ringing is informed that his call has been received at the central office. This 110 signal from the subscriber to the central office is sent over a metallic circuit, notwithstanding that the subscriber's ground is connected with the circuit at this time. The 115 construction and operation of this signaling apparatus is the same as that shown and described in my application for Letters Patent, Serial No. 710,757, filed March 28, 1899. The operator now shoves in the plunger of the calling subscriber, so as to close the 120 break in the line at the annunciator, and at the same time the operator shoves her coupling-plug V into the coupling-jack of the 125 calling subscriber and in so doing separates the contacts m m' of the jack and engages the plug-contacts v v' with the jack-contacts m m' , respectively, thereby looping the operator's listening and talking set into the calling-subscriber's line and forming a metallic talking-circuit between the subscriber and the 130 operator, which runs as follows: Beginning at wire d on one side of the transmitter of subscriber's station No. 1, the current passes successively through wire I, jack-contact m ,

operator's plug-contact v , wire v^3 , transmitter S, wire u , including battery U, primary induction-coil t , wire v^2 , plug-contact v' , jack-contact m' , wire o , annunciator-coils b^4 , contacts $o' o^2$, plunger and frame, wire p^7 , wire p^8 , contact p' , bridge p^9 , contact p , wire p^6 , main wire K, switch-lever H, contact d^3 , wire d^2 , primary induction-coil f , and wire d' to the opposite side of the transmitter. When the subscriber or the operator talks into his respective transmitter, the undulations produced thereby in the main electric circuit are reproduced by the induction-coils in the local electric circuits, which include only the receivers and the secondary induction-coils of the subscriber and operator. It will be observed that when the subscriber and operator are thus connected the electric current for the main circuit between these parties is supplied wholly by the battery U of the operator's talking and listening set, and this current is distributed uniformly between both the subscriber's and operator's apparatus, so that both parties can hear equally well. After learning with whom the calling subscriber wishes to be connected the operator withdraws her listening and talking plug V from the calling-subscriber's coupling-jack and then introduces the plug of her signaling apparatus into the coupling-jack of the subscriber who is wanted and rings him up. Any suitable signaling apparatus may be used in this system by the operator, that shown in the drawings being the same as that shown in my aforesaid application for Letters Patent, Serial No. 710,757, filed March 28, 1899. After having signaled the called subscriber that he is wanted the operator disconnects her signaling-plug from his coupling-jack and the operator takes the coupling-plug of the calling subscriber and shoves the same into the coupling-jack of the called subscriber. By this act of the operator the circuit across the bridge-contacts $p p'$ of the calling subscriber are broken and the contact members $n n'$ of the calling-subscriber's coupling-plug are engaged, respectively, with the jack-contacts $m m'$ of the called subscriber. Assuming that subscriber No. 1 has called up No. 300 and that both subscribers after being connected remove their receivers from the switch-levers, a metallic talking-circuit is formed between the two subscribers, which is shown in Fig. 1 and which is as follows: Beginning at wire d on one side of the transmitter of subscriber's station No. 1, the current passes successively through wire I, jack-contacts $m m'$, wire o , annunciator-coils b^4 of subscriber No. 1, contacts $o' o^2$, plunger and frame, wire p^7 , cord-wire p^5 , plug-contact n , coupling-jack contact m of subscriber No. 300, main wire I, wire d , transmitter E, wire d' , primary induction-coil f of subscriber No. 300, wire d^2 , contact d^3 , switch-lever H, main wire K, branch wire p^6 , contact p , bridge-contact p^2 , contact n' , branch wire p^8 , wire p^7 , frame and plunger of subscriber's annunciator No. 300, contacts $o^2 o'$, annunciator-coils, wire o , contact m' of subscriber's jack No. 300, contact n' of subscriber's plug No. 1, cord-wire p^4 , including battery Q, of subscriber No. 1, main wire K, switch-lever H, contact d^3 , wire d^2 , and primary induction-coil f to the opposite side of the transmitter of subscriber No. 1. When the subscriber talks into his transmitter, the undulations produced thereby in the main electric circuit are reproduced by the induction-coils in the local electric circuits, which include only the receivers and secondary coils of the subscribers, in the same manner as when the operator is talking to a subscriber. By arranging the battery, the transmitters, and the primary coils in the main circuit and the receivers and secondary coils in the local circuits the induced current through the secondary coils and receiver is confined to the subscriber's or operator's local circuits, thereby making it possible to transmit speech more clearly and over a greater distance than heretofore. Inasmuch as the primary circuit of the induction-coils and transmitters of both the connected parties are in circuit with the same battery in the main line, the current passing through both transmitters and primary coils is uniform through both sets of instruments and the operation of both transmitting devices is the same. After the subscribers have finished their conversation and both have hung up their receivers, so as to ground the main line at both stations, either subscriber upon operating his generator can give the ring-off signal to the central office, this current for this signal passing over a ground-circuit from one subscriber to another, as follows: Beginning at the ground of subscriber No. 1, the current passes successively through the ground-wire g' , ground-contact g , switch-lever H, generator-contact b , generator-coils, bell-coils, main wire I, jack-contacts $m m'$, coils b^4 , contacts $o' o^2$, plunger l and frame of subscriber's annunciator No. 1, wire p^7 , cord-wire p^5 , plug-contact n , jack-contact m , main wire I, bell-coils and generator-coils of subscriber No. 300, generator-contact b , switch-lever H, ground-contact g , and ground-wire g' to the ground of subscriber No. 300. This ringing-off circuit includes only the annunciator-coils of the subscriber whose plug is in use, whereby the plunger of this subscriber only is projected and the respective operator is notified that the conversation is finished. The operator now withdraws the calling-subscriber's plug from the called-subscriber's coupling-jack and returns the plug with its base upon the contacts $p p'$, so as to cross the same, and the operator also shoves in the plunger of the calling-subscriber's annunciator, thereby restoring both subscribers' lines to their normal condition. This ringing-off circuit is the same as in the application for Letters Patent referred to.

It will be observed that the battery Q of only one subscriber is in use for operating

the talking and listening apparatus of both subscribers which are connected. By arranging a battery Q in one of the plug-wires of each subscriber the battery of that subscriber is included in the main circuit, whose plug is used in effecting a connection between two subscribers, and the circuit of each battery is therefore always open unless its respective plug is coupled with the jack of another subscriber, thus avoiding wasting of the battery-power.

In the modification of my telephone-exchange system shown in Fig. 3 an annunciator W, with a pivoted indicator-apron w, is employed. This annunciator is so organized that the main line is not broken or opened by the annunciator when the subscriber sends a call to the central office, and the subscriber is therefore not notified that his call has been received, because his bell does not stop ringing. The annunciator-coils of both constructions shown in Figs. 1 and 3 are wound to a sufficiently-high resistance, so that the same cannot be operated by the transmitter-battery while the latter is placed in circuit when coupling two subscribers or when coupling a subscriber with the operator.

I claim as my invention—

1. The combination with a main circuit connecting a subscriber's station and a central office and a local circuit arranged at the subscriber's station, of a transmitter arranged in the main circuit at the subscriber's station, a receiver arranged in said local circuit, an induction-coil having its primary included in the main circuit and its secondary included in said local circuit, a coupling-jack arranged in the main circuit at the central office, a coupling-plug arranged at the central office and connected with the main circuit by a branch line, a battery included in said branch line, and a switch whereby said branch line and battery are cut off from the main circuit

when the plug is in its normal inoperative position and whereby said branch line and battery are included in the main circuit when the plug is shifted for connecting the same with the coupling-jack of another subscriber, substantially as set forth. 45

2. The combination with a main metallic circuit which connects a subscriber's station with a central office and which is normally closed and ungrounded at the central office, and a local circuit arranged at the subscriber's station, of a coupling-jack arranged in the main circuit at the central office, a transmitter arranged in one side of the main circuit, a receiver arranged in the local circuit, an induction-coil having its primary included in the side of the circuit containing the transmitter and its secondary included in the local circuit containing the receiver, said transmitter, receiver and induction-coil forming the subscriber's speaking apparatus, a signaling apparatus arranged at the subscriber's station in the same side of the circuit containing the transmitter, a switch whereby either the subscriber's signaling apparatus and ground or the subscriber's speaking apparatus are connected with the metallic circuit, an annunciator arranged at the central office in the opposite side of the main circuit, a coupling-plug connected by branch lines with the main circuit between the annunciator and the subscriber's station, bridge-contacts arranged in the main circuit on opposite sides of the plug branch lines and adapted to be connected and disconnected by a bridge on the plug, and a battery included in one of the plug branch lines, substantially as set forth. 50 55 60 65 70 75 80

Witness my hand this 6th day of May, 1899.
